VACUUM FEED DEVICE

Filed July 16, 1925

FIG.1.

FIG.2.

FIG.3.

UNITED STATES PATENT OFFICE.

JEAN A. H. BARKEIJ, OF LOS ANGELES, CALIFORNIA.

VACUUM FEED DEVICE.

Application filed July 16, 1925. Serial No. 44,129.

This invention relates to liquid fuel systems for explosive engines and it is particularly useful as an accessory to automobile and truck engines.

5 My primary object is to eliminate the complicated valve mechanisms and delicate construction in existing devices, reducing the number of valves to one.

10 My second object is to provide a sudden change between the partial vacuum condition and the atmospheric pressure condition.

15 Realizing that the present condition may be embodied in constructions other than those specifically shown and described, I desire that the disclosure herewith shall be considered as 20 illustrative and not in the limiting sense.

In the drawings:—

Fig. 1 is a transverse sectional view of a 25 vacuum feed device.

Fig. 2 shows a modified form of the vacuum chamber together with an additional air vent and a ball valve.

Fig. 3 shows another modified form of the 30 vacuum chamber together with a flat air valve and an additional air vent.

Referring to the drawings, in Fig. 1, 1 is a 35 vacuum or receiving tank, 2 is a gravity or feeding tank, 3 is an air valve, 4 is the seat for the air valve, 5 is a passage way for the valve stem 6 connecting rigidly said valve with a float, 8 is an additional open air vent, in constant communication with the suction line 9. 7, 9 is a pipe line connecting the inlet manifold of a motor or any suitable source of 40 suction with the vacuum chamber. 10 is an air vent for the gravity tank, 11 is an elbow, with a hinge or fulcrum 12 for a flap valve 13 to operate dependent upon the pressure in the vacuum tank. 14 is a feed pipe leading towards the carburetor 15. 16 is a feed pipe from the fuel tank, usually placed in the rear of the vehicle at a point below said vacuum tank, as is well known in the art.

The operation of the device is fundamentally different from the existing types. The 45 partial vacuum is suspended not by closing the suction pipe but by opening an air vent, so that the atmospheric pressure is furnished quicker than it is taken away from the source of suction. The area of the passageway 5 is greater than the area of the suction pipe 9. I prefer to connect the latter pipe directly to the passage 5 near the valve seat 4 in order to prevent any fuel being taken from the receiving chamber instead of air. This is of 50 particular importance in this system, where

the motor sucks most of the time a little stream of air by way of the vacuum tank. The valve stem 6 has to be sufficiently long to establish a sufficient distance between the 60 level of the fuel and the passageway 5.

The operation with an empty vacuum tank and a fuel low-level reservoir is as follows, considering for a moment that the air vent 8 is eliminated. The electric starter turns 65 the engine, the float presses the valve 3 on its seat 4. A partial vacuum is created in chamber 1. The float rises by the incoming fluid high enough to raise the valve 3 from its seat 4, and as the inlet area of passage way 70 5 is greater than that of suction pipe 9, no partial vacuum will be created and instead thereof the fluid will open by its gravity the flap valve 13 in the elbow 11 and feed towards the gravity tank 2, from which a pipe line 14 75 feeds it towards the carburetor 15.

In fact the fluid has to rise to a higher level in order to open the valve 3 than would be necessary if there were no difference of pressure below and above the valve 3, and on the 80 other hand, after the buoyancy of the float has opened the air valve and the fluid has dropped towards the tank 2 and the valve 3 has approached again its seat 4, then the difference of pressure below and above valve 85 3 will press the float down a little in the fluid. This sudden change both ways between the vacuum producing position and the atmospheric pressure condition, causes a positive 90 action and prevents the valve from fluttering or chattering. The valve has no tendency to stick as there is no mechanism to open and close two valves or two openings at the same time as in the prior art. The amount of air which will be sucked continuously through pipe 9 does not affect appreciably even the idling of the motor of a small 95 passenger car, although the nature of the mixture has to be a little richer to compensate for the extra air. In case another source 100 of suction is used this effect upon the mixture will be entirely avoided.

Referring to Fig. 2 it is seen that this vacuum tank differs from that in Fig. 1 in four respects. The suction pipe 9 provided with 105 a valve 21 is not connected with the passage way 5 but simply ends into the head of the tank 1. The valve is not conical but spherical and an air vent of very small diameter is provided at 8. The form of the tank is such 110 that the horizontal cross section increases rapidly from the bottom towards the top.

This is done for special conditions, in which it is desirable that only a greater quantity of fuel will act upon the valve 3 than in Fig. 1 or another modified form of the vacuum tank as shown in Fig. 3.

The advantage of having the air vent 8 is that in case the engine is stopped, when the valve 3 is seated, that said air vent will allow the fuel to gravitate towards the carburetor. The valve closes the air passages 5 by the weight of the float so securely that no air might enter if the suction pipe 9 is connected with a source of suction which would not admit air when the engine stops running. The disadvantage might be supposed to be that the vacuum might be impaired too much, but that is not the case even if the pipe 9 is connected with the manifold of the engine instead of with a stronger source of suction. Even at high engine speeds when the vacuum is little, the air vent 8 might even increase the suction and the vacuum in the tank 1, if placed in close proximity thereto. If the valve begins to unseat, the partial vacuum is quicker eliminated as the air vent will help to increase the volume of air so that no balance between the air pressure on top of the valve and the buoyancy will occur, nor a balance between the volume of air sucked way and admitted.

The air vent 10 of the gravity tank is of course necessary for the operation of the valve 13.

The form in Fig. 3 differs in five respects from that shown in Fig. 1. Here again is the suction pipe 9 not connected with the passageway 5, a small air vent 8 is provided, a flat valve 3 is provided instead of a conical or spherical valve, the suction pipe is provided with device to decrease or increase the area of the pipe 9 by turning the wing screw 21. This valve, like the one in Fig. 2 may have the same function as the valve 3 in effecting an atmospheric and subatmospheric pressure in said tank and may have of course the same function of interrupting the communication between the additional air vent 8 and the suction connection 9 by connecting it operatively with the movement of the float, which latter construction is well known in the prior art. Whether the cooperating function between these two connections is interrupted from one side or the other makes little difference.

The valve 3 when seated has a top surface exposed to the atmosphere considerably in excess of the undersurface exposed to the partial vacuum in the tank 1. The pressures on either side of the valve differ therefore not proportional to the pressures on either side of this valve, but the pressure on the top side of the valve is so much greater in proportion to the respective areas. The float has to exert a greater pressure to lift the valve 3 from its seat 4, and the valve approaching

the valve seat closely, will suddenly press the float a little in the fluid when closing. The upper surface should be smaller in proportion than the maximum buoyance of the float. The form of the float and tank is the reverse of that shown in Fig. 2. A small quantity of gasoline will act upon the valve 3 as the horizontal cross section decreases rapidly towards the top of the tank. The gravity tank is entirely dispensed with in this arrangement and only a single chamber constitutes both vacuum and gravity tank. The pipe 9 is supposed to be connected with a source of suction of such a power that the amount of fluid will be replenished almost instantly so that the interruption of gravity flow to the carburetor during the time of filling the vacuum chamber will be of such a short duration that it will not affect the proper functioning of the carburetor. The special form of the tank is of great help towards this purpose. It is however understood that this arrangement can be combined with the gravity tank of Figs. 1 and 2, equally as the additional air vent 8 may be combined with the arrangement of Fig. 1.

The disc 17 is sucked upwardly against the seat 18 and it will, as soon as the valve 3 opens by the buoyancy of the float 7, be opened by the gravity of the fluid in chamber 1. The disc 17 seats downwardly on a ring 19 provided with holes to establish the necessary communication with pipe 20 which will be of ample diameter to act as a reservoir.

I claim:

1. A vacuum feed device comprising a chamber having a suction connection in constant communication therewith, a valve controlled atmospheric connection, a liquid fuel supply connection, and a valve controlled liquid fuel outlet, an additional continuously open air vent in constant communication with said suction connection during the entire operation of said vacuum tank to increase the suction; said first valve actuated by the change of the liquid level in said chamber, said second valve actuated by the closed and open position of said first valve.

2. A vacuum feed device comprising a chamber having a permanent suction connection, a valve controlled atmospheric connection, a second continuously open air vent, a liquid fuel supply and a valve-controlled liquid fuel outlet, said first valve actuated by the change of the liquid level in said chamber and a float having connections by which the float operates said valve.

3. A vacuum feed device comprising a receiving vacuum chamber, and a gravity chamber, a valve controlled connection between said two chambers, a fuel outlet for said gravity chamber and a continuously open air vent to drain said fuel from said chamber, a continuously open vacuum connection for said vacuum chamber and a continuously open air

vent for said chamber, a fuel inlet connection for said vacuum chamber, said latter air connection being in constant communication with said vacuum connection to increase the suction of said latter connection; a valve controlled atmospheric connection, said latter valve operated by the level of the liquid in said vacuum chamber.

4. A vacuum feed device comprising a vacuum chamber and a gravity chamber, a valve controlled connection between said chambers, continuously open air vents for said gravity chamber and for said vacuum

chamber, a continuously open fuel outlet for said gravity chamber; a valve controlled fuel outlet for said vacuum chamber; a fuel inlet and a vacuum connection in said vacuum chamber in constant communication with said continuously open air vent at least during the filling of said chamber through said fuel inlet; additional means to effect an atmospheric and subatmospheric pressure in said vacuum chamber, said means operated by the level of the fluid in said vacuum chamber.

JEAN A. H. BARKEIJ.
